UNITED STATES PATENT OFFICE.

PAUL E. FLEMING, OF CHICAGO, ILLINOIS.

CARD-SPREADING DEVICE.

Application filed October 21, 1921. Serial No. 509,445.

To all whom it may concern:

Be it known that I, PAUL E. FLEMING, a citizen of the United States, residing at Chicago, in the county of Cook and State of Illinois, have invented new and useful Improvements in Card-Spreading Devices, of which the following is a specification.

This invention relates to devices for spreading file or index cards, leaves, pages and the like so that a ready and quick reference may be had to the cards or leaves without removing them from the member or means by which they are carried.

One object of my invention is to provide a rockably mounted member for holding the cards and to effect the spreading of them upon the rocking of said member.

Another object of my invention is to provide means whereby the cards when loose in the member carrying them will be prevented from moving out of proper position upon being released from the spreading member and flexing outward therefrom during the spreading operation.

25 A further object of my invention is to permit the cards in front of the spreading member, when the tension thereon is released, to be readily and easily withdrawn from and inserted back into place or partially raised whenever a detailed inspection of a card is desired during the spreading operation.

35 A further object of my invention is to raise the spreading member by contact with the cards as they are returned to starting position, and thus permit the cards to pass under said member without spreading the cards on their return movement.

The invention consists further in the matters hereinafter described and more particularly set forth in the appended claims.

In the accompanying drawings—

Fig. 1 is a perspective view of a card-spreading device constructed in accordance 45 with my invention;

Fig. 2 is a top plan view of said device;

Fig. 3 is a vertical sectional view taken on line 3—3 of Fig. 2;

50 Fig. 4 is a similar view showing how a card may be removed from the group during the spreading operation; and

Fig. 5 is a view of a detail of construction to be hereinafter described.

For illustrative purposes, the device of my 55 invention is shown in the drawings in the form of an office tickler and comprises a box-

like frame or case 1 open at the front and having two end walls 2, 2, a rear wall 3, all upright, and a flat bottom wall 4. These walls are suitably connected to make the case or support 1 rigid and capable of sitting upright on a desk or other place where the device is used.

60 Located in the case 1 is a container or tray-like member 5, horizontally arranged above the wall 4 and extending between the end walls 2, 2. The tray 5 opens upwardly to receive and contain therein a plurality or group of index cards or leaves 6, 6. These project above the tray and have their upper or free edges in the same plane. The tray 5 has depending end plates 7, 7 fixed to a horizontal rock shaft 8 between the bottom of the tray and the bottom wall 4. This shaft 8 extends between the end walls 2, 2 65 and has its ends journaled or rockably mounted therein.

70 For oscillating or rocking the tray 5, I provide an arcuate rack bar 9 fixed to the tray at one end thereof and between the same and one of the end walls 2 of the case. Extending outward from said end wall 2 is a tubular bracket 10, in which is journaled a shaft 11. This shaft extends through said end wall 2 and has fixed to its inner end a pinion 12 in mesh with said rack bar 9. Fixed to the outer end of said shaft 11 is a hand wheel 13 so that the tray 5 may be rocked back and forth, for spreading the cards 6 in the manner to be presently described.

75 Secured to the rear wall 3 is a bracket 14 extending above the upper edge of that wall, as shown in the drawings, and provided with two parallel bracket arms 15, 15 extending over the upper or free edges of the cards 6. Between these arms 15, 15 at the outer ends thereof is located a relatively heavy or weighted spreading member or roller 16 having its trunnions 17 in arcuate slots 18 in 80 the arms 15, 15, as shown. These slots are arranged generally oblique to the swinging movement of the cards and extend upward and inward toward the inner ends of the arms 15, 15.

85 The device is operated or used in the following manner. Normally the cards 6 are in a position to the rear of the roller 16 and rest against the rear wall 3 of the case 1, unless the rack 9 has a stop member to hold the cards out of contact with said wall. The handle 13 is turned in a direction to swing

the cards 6 and tray 5 outward toward and under the roller 16. When the cards come in contact with the roller 16, the pressure on the roller is outward, with the result that the roller is maintained at the bottom of the slots 18. A continued outward rocking of the cards 6 causes them to be flexed or bent backward as they pass under the roller 16 and when freed from the roller swing or flex quickly outward to effect a sufficient spreading of the cards to permit the operator having a view of the index or other data appearing on the face of the several cards as they are flirted or spread by the roller.

In order that the free or upper edges of all the cards contained in the tray 5 will be spread by the roller 16, the bottom surface 19 of the tray is curved or rounded to conform to the arc of movement of the tray with the shaft 8, this causing the upper or free edges of all the cards to contact with the roller 16 as they are moved under it. The front portion of this curved surface 19 in extending downward permits the lower portions of the front half of the cards as they are bent backward to be forced or compressed in tight contact with each other to prevent the cards as they are freed from the roller from jumping upward or being otherwise displaced out of proper position in the tray. The rear portion of this curved surface 19 in extending upward together with the downward pressure on the rear half of the cards by the roller 16 resists the tendency of the lower edges of such cards to be forced into tight contact with the front half of the cards and thus produces a balanced condition. This facilitates the spreading action and allows the cards as released from the roller to be readily removed or raised for inspection, as the lower portions of the cards in the two sections are not held in such tight contact that they cannot be easily raised.

Spreading of all the cards is accomplished by moving them under and beyond the roller 16. To return the cards to position behind the roller, in order to be ready for an additional spreading, the handle 13 is turned in the opposite direction to swing the tray 5 back into starting position and, by reason of the slots 18, the roller 16 is raised by contact with the cards and allows them to pass freely under the roller without having any spreading action on them in the return movement, as indicated in Fig. 5.

By the construction described the cards 6 may be spread at any speed desired, either fast or slow, as the user may require, and may be stopped at any point in the spreading action in order that the operator may view any one or more of the cards in the group. Should it be desired to stop the operation at any point in the group so as

to further inspect the card at that point, rotation of the handle 13 is stopped and the grasp thereon loosened. This permits the tray 5 to fall back and the roller 16 drops into the space between the cards to the rear and front of the roller, as indicated in Fig. 4. The tension on the cards being released, any card in front of the roller 16 may be readily and easily withdrawn from the tray, as shown in said Fig. 4. As the compression on the lower portions of the cards is relieved to permit this being done, the card or cards withdrawn may be readily and easily inserted in place back into the tray and the spreading continued or started over again by moving the cards back to starting position.

While I have shown and described my invention as applied to an office tickler, it is of course to be understood that my invention may be applied to a card drawer, or be used to spread the pages of a book, such as a telephone or other directory, by placing the same in a tray such as 5. I do not wish to be limited to the details of construction and arrangement of parts shown, as they may be variously changed and modified without departing from the spirit and scope of my invention.

I claim as my invention:

1. A card-spreading device, comprising a rockably mounted member, a group of cards arranged one behind the other and carried by said member with their free edges beyond the same, means for rocking said member, and means acting on the free edges of said cards to spread the same by bending said edges backward in succession upon the rocking of said member.

2. A card-spreading device, comprising a rockably mounted member, a group of cards arranged one behind the other and carried by said member with their free edges beyond the same, means for rocking said member, and means arranged in the path of movement of said cards for spreading the same by bending their free edges backward in succession as the cards are swung with said member into contact with and past said means.

3. A card-spreading device, comprising a rockably mounted member, a group of cards arranged one behind the other and carried by said member with their free edges beyond the same, means for rocking said member, and means arranged in the path of movement of said cards for spreading the same by bending their free edges backward in succession as the cards are swung outward with said member into contact with and past said means from one side thereof to the other, said means being mounted to be raised by the cards when swung back to starting position without spreading the cards.

4. A card-spreading device, comprising a rockably mounted member, a group of cards arranged one behind the other and carried by said member with their free edges beyond the same, a roller arranged in the path of movement of said cards, and means for rocking said member for carrying said cards into contact with and past said roller for spreading said cards by bending their free edges backward in succession as the cards are moved outward from said roller. 5
5. A card-spreading device, comprising a rockably mounted member, a group of cards arranged one behind the other and carried by said member with their free edges beyond the same, a roller arranged in the path of movement of said cards, means for rocking said member for carrying said cards into contact with and past said roller for spreading said cards by bending their free edges backward in succession as the cards are moved outward from said roller, and means mounting the roller to be raised by contact 10 with the cards upon returning the cards to the rear of said roller. 15
6. A card-spreading device, comprising a rockably mounted tray, a group of cards loose in said tray one behind the other and having their free edges beyond the same, a roller arranged in the path of movement of said cards, and means for rocking said tray for swinging said cards into contact with and past said roller for spreading said cards by bending their free edges backward in succession as the cards are carried beyond said roller. 20
7. A card-spreading device, comprising a rockably mounted tray, a group of cards loose in said tray one behind the other and having their free edges beyond the same, a member arranged in the path of movement of said cards, and means for rocking said tray for swinging said cards into contact with and past said member for spreading said cards by bending their free edges backward in succession as the cards are carried beyond said member; said tray being constructed to cause the portions of the cards therein to be held in tight contact with each other during the flexing of the cards by contact with said member and loosening the tight contact of the cards with each other upon relieving the flexing of the cards by said member. 25
8. A card-spreading device, comprising a rockably mounted tray, a group of cards loose in said tray one behind the other and having their free edges beyond the same, the bottom wall of said tray being rounded in section in a plane transverse to the axis of rocking movement thereof, a roller arranged in the path of movement of the free edges of said cards, and means for rocking said tray for carrying the cards into contact with and past the roller for spreading the same. 30
9. A card-spreading device, comprising a rockably mounted tray, a group of cards in said tray one behind the other and having their free edges beyond the same, a roller arranged in the path of movement of the free edges of said cards, a bracket for said roller and having arcuate slots therein arranged vertical and generally oblique to the swinging movement of said cards, said roller 70 having trunnions in said slots, and means for rocking said tray for carrying the free edges of said cards into contact with and past said roller. 75
10. A card-spreading device, comprising a rockably mounted tray, a group of cards in said tray one behind the other and having their free edges beyond the same, a roller arranged in the path of movement of the free edges of said cards, a bracket for said 80 roller and having arcuate slots therein arranged vertical and generally oblique to the swinging movement of said cards, said roller having trunnions in said slots, an arcuate rack bar carried by said tray, a shaft, a pinion on said shaft in mesh with said rack bar, and a hand wheel on said shaft for turning the same. 85
11. A card-spreading device, comprising a rockably mounted member, a group of cards arranged one behind the other and carried by said member, means for rocking said member, and means acting upon the rocking of said member to spread said cards. 90
12. A card-spreading device, comprising an upright case open at the front, a tray rockably mounted in said case, a group of cards in said tray and having their free edges extending upward above the same, a roller supported by said case above said 100 cards and in the path of movement of the free edges thereof, and means for rocking said tray for carrying said cards into contact with and beyond said roller. 105

In testimony that I claim the foregoing 110 as my invention, I affix my signature this 18th day of October, A. D. 1921.

PAUL E. FLEMING.
